UNITED STATES PATENT OFFICE.

WILLIAM G. WILLIAMS, OF KINGWOOD, WEST VIRGINIA, ASSIGNOR OF ONE-HALF TO
ARTHUR GRIBBLE, OF KINGWOOD, WEST VIRGINIA.

SPARK-PLUG TESTER.

Application filed October 7, 1924. Serial No. 742,170.

This invention relates to an improved device, which may well be designated a spark plug tester.

The invention has reference to a device of this class, which is either portable or fixedly mounted on the instrument or dash board of an automobile, the device being constructed in a manner to permit an accurate test of the plug to be made, while the engine is running.

One feature of the invention is the provision of a unit composed of a plurality of conventional plug testers, this unit being slidably and removably mounted in an appropriate casing, so that it can be moved at will to a position to permit the current to pass successively through the tester, and to permit the test to be made while the engine is under a stress.

Another feature of the invention is to utilize in connection with this removable and slidable tester unit, a manually rotated cam or eccentric which serves to slide the unit in a direction to make the test or to move the eccentric to a position to permit the unit to move in an opposite direction, under the action of the springs, to render the device ineffective.

A further feature of the invention is the embodiment in the structure of a plurality of sleeves of insulation material, in which contacts are adjustably and slidably mounted in the position to co-act with movable contacts on the aforesaid tester, these adjustable contacts being equipped with individual wires, to lead to and be connected with the plugs, adapting the device for individual or public garage use.

Other features and advantages of the invention will become apparent from the following description and drawings.

In the drawings:

Figure 1 is a view, partly in section, and partly in elevation, showing a spark plug tester constructed in accordance with the invention.

Figure 2 is an edge elevational view thereof.

Figure 3 is a fragmentary front elevation.

The device shown in the present application is especially adapted for a four cylinder automobile engine, but it is to be understood that it may well be varied to act in conjunction with engines having more or less cylinders.

In carrying out the invention, I employ four conventional spark plug testers 1. These are of the elongated formation, and are provided at their reduced ends with suitably designed contacts 2. Between their ends they are provided with sight openings 3, for exposing a spark gap (not shown), which is disposed within the structure. Devices similar to these are now marketed, and are used, and since the structure is well known, a more detailed description is unnecessary. As said, I use four of these testers 1, and I combine them into a single unit, spacing the same apart by appropriate spacers 4. Connected to the unit at one end is an arched bar 5, and a pair of coil springs 6 are connected to this bar, and are anchored at their opposite ends in an elongated casing 7. The casing is of any suitable design, and is shaped to accommodate the unit just described. It may, if desired, be provided with a cover 8, and the cover in turn may be provided with an elongated exposure slot 9, to permit the sight openings 3 to be seen therethrough. It is obvious that this tester unit is bodily slidable within the casing, and in order to operate it, I provide a disc 10, which is arranged for rotation in the chamber formed between the bar 5 and the adjacent end of the casing. This disc is provided with an elongated slot 11, and with a stop 12, for cooperation with the complementary stop 13, on the casing, to limit its rotary movement. It is noted that the slot is disposed eccentrically.

Passing through the slot is a rotary shaft 14, journaled in an appropriate bearing. The shaft is provided with screw threads and lock nuts 16 are threaded thereon, on opposite sides of the disc to clamp the latter to the shaft. On its outer end, the shaft is provided with a knob 17^a, by means of which it is rotated. It is obvious that with this arrangement, when the shaft is rotated, the eccentric, formed by the disc, will press against the bar 5, and will feed the tester units forwardly. The casing may be opened, adjacent the contact carrying end of the tester, and in this open end, a plurality of sleeves 17, of appropriate insulation may be fitted. Adjustably arranged in these sleeves are appropriate contact members 18, in the present instance of bifurcated formation. Arranged between the bifurcations is a bolt, the head of which is designated as 110

- 19, and is arranged for cooperation with the aforesaid contact 2. A conical nut 20 is threaded on the shank of the bolt and is arranged between the furcation of the contact member to force these into frictional contact with the cooperating sleeve, to anchor the contact member in place. One end of a conductor wire 21 is mounted, or otherwise connected with one of the furcations. Although I have not shown it, the opposite ends of these wires will be provided with clips or appropriate means, to permit them to be connected to the spark plugs of the cylinders.
- 15 In practice, the casing may be mounted upon the instrument board, at a point to permit the sight openings 3 to be readily viewed. If, at any time, engine trouble is experienced while a run is being made, the spark plugs may be tested to ascertain whether or not the trouble exists there. In making this test, the knob 17 is depressed, and the shaft 14 turned in a direction to move the eccentrically arranged disc in a manner to feed the testers longitudinally in the casing, bringing the contacts 2, with which they are equipped, into engagement with the bolt heads 19 of the stationary contacts. The current will then pass through the device, and through the medium of the sight opening, it can be ascertained whether or not the plugs are acting properly. Although I have shown the preferred and specific embodiment of the invention, I do not wish to be limited to the precise details illustrated, for changes coming within the scope of the adjoined claims may be resorted to, if desired.
- I claim:
- 40 1. In a spark plug testing device of the class described, a casing of elongated form, said casing being substantially flat and oblong in cross section, a plurality of sleeves fitted into one end of the casing, contacts

arranged in said sleeves, conductor wires 45 connected with said contacts, and a plug testing unit slidably mounted in the casing, said unit being made up of a plurality of conventional self contained spark plug testers arranged in side by side abutting relation, each tester comprising a body having a contact at one end cooperable with the adjacent one of the first named contacts, a sight opening for a spark gap, a transparent closure for the sight opening, means connecting all of said testers together to group them together forming said unit, and means in such casing for sliding said unit to render said testers effective.

2. In a spark plug testing device of the 60 class described, a casing of elongated form, said casing being substantially flat and oblong in cross section, a plurality of sleeves fitted into one end of the casing, contacts arranged in said sleeves, conductor wires 65 connected with said contacts, and a plug testing unit slidably mounted in the casing, said unit being made up of a plurality of conventional self contained spark plug testers arranged in side by side abutting 70 relation, each tester comprising a body having a contact at one end cooperable with the adjacent one of the first named contacts, a sight opening for a spark gap, a transparent closure for the sight opening, means connecting all of said testers together to group them together for forming said unit, means 75 in said casing for sliding said unit to render said testers effective, said means comprising an eccentric cooperable with said connecting 80 means, operating means for the eccentric, and spring means connected with said casing and with said unit for moving the unit in a direction to render it normally ineffective.

In testimony whereof I affix my signature.

WM. G. WILLIAMS.
